UNITED STATES PATENT OFFICE.

WILLIAM T. HOPSON, OF LEXINGTON, MISSISSIPPI.

BRIDLE.

1,296,806.

Specification of Letters Patent. Patented Mar. 11, 1919.

Application filed December 5, 1918. Serial No. 265,382.

To all whom it may concern:

Be it known that I, WILLIAM T. HOPSON, a citizen of the United States, residing at Lexington, in the county of Holmes and State of 5 Mississippi, have invented certain new and useful Improvements in Bridles, of which the following is a specification.

This invention relates to bridles and has for a primary object the construction of a 10 bridle which may be quickly and easily adjusted for use on different sizes of animals, without limiting the advantages of the bridle in any way.

A further object is to avoid the use of a 15 cumbersome and unsightly device without surrendering any of the characteristic features of standard bridles, at the same time permitting of such a complete adjustability that the bridle is adapted for use with 20 almost any sized animal.

Other objects of the invention will be in part described and in part understood from the following description of the present preferred embodiment taken in conjunction 25 with the drawings, in which:—

Figure 1 is a side elevational view of a bridle constructed in accordance with my invention illustrating the application of same.

Fig. 2 is a perspective view of the combination crown and head straps, illustrating the manner in which they are connected to the throat strap.

Fig. 3 is a side elevational view of the bridle showing the upper and lower units removed.

Fig. 4 is a perspective view of the combined nose and jaw straps, and

Fig. 5 is a detail enlarged fragmentary 40 sectional view of the device showing particularly the manner in which the blinders are connected with the cheek straps.

The bridle consists of upper and lower units 1 and 1' respectively, the upper unit 45 comprising a crown strap 2 and head strap 3 while the lower unit a nose strap 4 and jaw strap 5. The ends of the straps 2 and 3 are fixedly engaged with rings 6. The ends of strap 4 are fixedly engaged with rings 7.

The jaw strap 5 is detachably engaged with the rings 7 as shown to advantage in Fig. 4 to permit the adjustment of said strap if desired.

The upper and lower units are adjustably 55 engaged by cheek straps 8 each of which in the present instance consists of a main strap

9 the upper end of which is engaged with a snap fastener 10. Said upper end of strap 9 is provided with a plurality of openings 11 so that when the free terminal of the strap 60 is folded upon itself certain of the openings will aline, these openings being adapted to register with openings in stays 12. Any suitable means may be used for engagement through such alining openings in order to 65 secure said strap 9 to the stays 12. In the instant case small strands of raw hide 13 are used. The other component part of the cheek strap 8 is an auxiliary strap 14 one end of which is engaged with one of the 70 rings 7, said end being also provided with a plurality of openings adapted to aline when the free terminal of the strap is folded upon itself after having been passed through the ring 7. Certain of the stays 12 are also 75 detachably engaged with the auxiliary strap in a manner identical with that above recited in connection with the main strap 9. The upper end of the auxiliary strap carries a buckle 15 for engagement with the free end 80 of the main strap 9.

Blinders 16 of the usual or any desired configuration are secured between the stays 12 by means of rivets or the like, it being apparent from the drawings that each stay 85 consists of a pair of parallelly arranged straps the upper series of which are secured to the blinders at right angles to the cheek straps 8, while the lower series of stays are preferably secured at an angle oblique to the cheek 90 straps.

A throat strap 17 is used which is intermediately connected to the crown strap 2 and is also connected at substantially diametrical points to throat latches 18. It will 95 be noted that the throat latches are adjustably engaged with rings 6 whereby adjustment of the throat strap forwardly or rearwardly of the animal will be permitted. The free ends of the throat strap are equipped 100 with corresponding buckle and aperture connections so that adjustment of said straps circumferentially of the animal's neck will be permitted.

A bit 19 of any desired form is detachably 105 engaged with the rings 7 through the medium of snap hooks 20. As is obvious therefore the bit may be removed when desired permitting use of this invention as a halter enabling the animal to be fed and watered 110 without inconvenience.

In use of this device it will be observed

that the lower unit 2 may be adjusted independently of any other part of the bridle by merely removing the raw hide connecting strands, and moving the unit to the desired 5 adjusted position, then repassing the strands through the openings in the auxiliary strap 14, which are in alinement. The upper unit 1 may be correspondingly adjusted when desired. The blinders will of course of necessity 10 become disengaged by removal of the raw hide strands, but it is understood that the blinders may be reengaged with the cheek straps so as to lie in the same position, with respect to the animal, as they did before the 15 adjustment was made. However if desired the blinders may be simultaneously adjusted with the adjustment of the cheek straps. It is also my desire to provide a bridle which can be removed except for the head stall and. 20 throat strap to prevent irritation of fractious animals frequently caused by bringing the bridle in contact with the ears of the animal.

It is to be understood that minor changes 25 in details of construction, proportion and

arrangement of parts may be made without departing from the spirit and scope of my invention.

What I claim is:—

1. A bridle including upper and lower 30 units adjustably connected together, a throat strap pivotedly engaged with the upper unit at one point and adjustably connected with said unit at diametrically opposite points.

2. A bridle including upper and lower 35 units adjustably connected together and a throat strap pivoted on said upper unit, throat latches connecting said strap to said upper unit and means adjustably connecting the ends of said strap.

3. A bridle including upper and lower units, the latter carrying a bit and cheek straps, and snap hooks carried by the cheek straps and engageable with the upper unit whereby said lower unit bit and cheek straps 45 can be removed from the animal independently of the upper unit.

In testimony whereof I affix my signature.

WILLIAM T. HOPSON.
